(57) **CLAIM**

The ornamental design for rolling luggage, as shown and described.

DESCRIPTION

FIG. 1 is a perspective view of an embodiment of luggage according to our new design;

FIG. 2 is a front elevation view thereof;

FIG. 3 is a rear elevation view thereof;

FIG. 4 is a left side view thereof;

FIG. 5 is a right side view thereof;

FIG. 6 is a top view thereof; and,

FIG. 7 is a bottom view thereof.

The short broken lines shown in the drawings represent claimed stitching while the long broken lines represent unclaimed portions of the rolling luggage and form no part of the claimed design.

1 Claim, 6 Drawing Sheets
